UNITED STATES PATENT OFFICE.

GEORGE RICHARD McCABE, OF ELKHORN, WISCONSIN.

PENCIL.

Application filed April 24, 1923. Serial No. 634,331.

To all whom it may concern:

Be it known that I, GEORGE R. McCABE, a citizen of the United States, and a resident of Elkhorn, in the county of Walworth and State of Wisconsin, have invented a new and Improved Pencil, of which the following is a full, clear, and exact description.

This invention relates to a pencil, and has for an object the provision of a pencil having a refillable lead and means for feeding it as used.

Another object resides in the provision of means whereby the construction and operation is rendered exceedingly simple and the manufacture most economical so that the device can be put on the market very inexpensively.

The invention is illustrated in the drawings, of which—

Figure 1 is a vertical longitudinal section;

Fig. 2 is a transverse section on the line 2—2 of Figure 1; and

Fig. 3 is a section on the line 3—3 of Fig. 1.

The form of the invention shown in the drawings is a preferred form, although it is understood that modifications in the construction and arrangement of the parts and in the character of the materials used may be adopted without departing from the spirit of the invention.

The preferred form of the invention as shown in the drawings comprises a pencil barrel 1 having a tapered lower end 2 and an open upper end threaded as at 4 and adapted to be closed by a flange cap 3 into the lower face of which a feed nut sleeve 5 is fixed. This sleeve extends downwardly within the barrel 1 and acts as a guide for a feed nut 6, the shape of the nut preferably being hexagonal and the sections of the sleeve being hexagonal so that the nut can slip up and down within the sleeve but will not rub therewithin.

A threaded feed screw extends downwardly within the barrel 1 and passes through

the nut 6. This feed screw, at its upper end, is in the form of a stem 8 passing through the cap 3 and embedded firmly within an operating thumb nut 10 between which and the collar 9 fastened on the screw 7 the stem 8 is firmly held. Dependent from the nut 6 on one side of the feed screw 7 is a lead-feeder rod 11 on the lower end of which is a lead holder 12. This lead holder is bent or offset from the feeder 11 so that the holder is in line with the screw 7 and the opening in the tapered end 2. A lead 13 is disposed in any suitable manner in the holder.

By turning the operating nut 10, the feed screw is rotated to cause the nut 6 to be moved up and down within the sleeve 5, whereby the lead feeder 11 is moved downwardly or upwardly to advance or withdraw the lead 13.

It will be understood that this device is exceedingly simple in its construction, involving the use of a minimum number of parts, capable of being economically assembled and yet being strong and durable; and there are a minimum number of parts to get out of order and to be repaired in operation.

What I claim is:—

A pencil, comprising a barrel having a tapering lower end, the barrel for the remainder of the length being of uniform diameter and having its upper end internally threaded, a flanged and threaded cap screwed into the upper end of the barrel, said cap having a central aperture, a polygonal sleeve in the barrel and having its upper end secured to the cap, a feed screw having at its upper end a stem extending through the aperture of the cap, a thumb nut secured on the end of the screw projecting through the cap, a collar on the screw and engaging the underside of the cap, a polygonal nut on the screw, and a feeder rod secured to the nut and carrying at its lower end a lead holder.

GEORGE RICHARD McCABE.
